Primary Examiner — Karen E Eldridge Powers(74) *Attorney, Agent, or Firm* — Dilworth & Barrese, LLP(57) **CLAIM**

The ornamental design for a pool brush handle, as shown and described.

DESCRIPTION

FIG. 1 is a top perspective view of a pool brush handle showing our new design;

FIG. 2 is a top view thereof;

FIG. 3 is a side view thereof;

FIG. 4 is an end view thereof; and

FIG. 5 is a top perspective view of the pool brush handle of FIG. 1, with two sections thereof slightly separated;

FIG. 6 is a top view thereof;

FIG. 7 is a side view thereof; and,

FIG. 8 is an end view thereof.

Broken and/or phantom lines are for environmental structure only and form no part of the claimed design.

1 Claim, 8 Drawing Sheets(56)
